UNITED STATES PATENT OFFICE.

DUDLEY H. FLYNT, OF GRAND ISLAND, NEBRASKA, ASSIGNOR OF ONE-HALF TO WOOD W. WHITE, OF NORTH PLATTE, NEBRASKA.

CABOOSE SIGNAL-LAMP.

No. 831,273.

Specification of Letters Patent.

Patented Sept. 18, 1906.

Application filed January 30, 1906. Serial No. 298,637.

To all whom it may concern:

Be it known that I, DUDLEY H. FLYNT, a citizen of the United States, residing at Grand Island, in the county of Hall and State of Nebraska, have invented new and useful Improvements in Caboose Signal-Lamps, of which the following is a specification.

My invention relates to improvements in caboose signal-lamps.

The object of my invention is to provide a caboose signal-lamp having novel means for quickly and accurately displaying forwardly or rearwardly different-colored lights.

The peculiarities of my invention are hereinafter described and claimed.

In the accompanying drawings, illustrative of my invention, Figure 1 is a central vertical transverse sectional view of a portion of the caboose-roof having mounted thereon a signal-lamp of my invention. Fig. 2 is a bottom view of what is shown in Fig. 1. Fig. 3 is a horizontal sectional view taken on the dotted line *a b* of Fig. 1. Fig. 4 is a horizontal sectional view taken on the dotted line *c d* of Fig. 1. Fig. 5 is a front elevation view of the signal-lamp, part of the roof being shown in vertical section and part broken away, the lamp-supporting device being shown in the lower position. Fig. 6 is a side elevation view of the lamp-support shown in the horizontal position and a portion of the mechanism to which the lamp is attached. Fig. 7 is a vertical cross-section view of a portion of the support for the tubular frame, one of the frame-rollers being shown in elevation and mounted on said support. Fig. 8 is a vertical sectional view taken on the dotted line *e f* of Fig. 7.

Similar characters of reference denote similar parts.

1 denotes a portion of the caboose-roof, and 2 two of the transverse rafters thereof.

3 denotes a rectangular casing mounted on the roof and provided with an open lower end registering with a vertical hole 4 in the roof 1. The casing 3 is provided in its front and rear sides with the openings 5 and 6, respectively. Rotatively mounted in the casing 3 is a vertical, tubular, cylindrical frame 7, supporting four vertical light-transmitting devices 8, 9, 10, and 11, respectively, said devices being preferably of glass, the device 8 being preferably red in color and the devices

9, 10, and 11 made of green glass. Said colored glasses are disposed so as to register each with the openings 5 or 6 when the frame 7 is rotated to the proper positions. The frame 7 is provided with four peripheral projections 12, on which are mounted, respectively, the rollers 13, mounted upon a support comprising the following described mechanism: 14 denotes a substantially horizontal plate secured to the under side of the roof 1 and provided with two vertical flanges 15, secured, respectively, to the two rafters 2. The plate 14 is provided with a central opening through which the frame 7 may be inserted and is also provided with a series of recesses communicating with said central opening and adapted to be closed by a series of closures 16, respectively, comprising each a horizontal slidable plate mounted upon the upper side of the plate 14 and provided each with an upwardly-extending flange 17, adapted when the closures are in the positions shown in Figs. 2, 3, 4, and 7 to form with the upwardly-extending flanges 18 on the plate 14 an annular track upon which the rollers 13 may travel when the frame 7 is rotated. Secured to the inner periphery of the frame 7 adjacent its lower end is a flat spring 19, the free end of which has secured to it a right-angled wire 20, having one vertical leg and a horizontal leg adapted to enter either of the openings 21, provided in three of the flanges 18, as shown in Fig. 3. The horizontal portion of the right-angled wire 20 extends through an opening provided therefor in the frame 7. By swinging the free end of the spring 19 inwardly the horizontal arm of the right-angled wire 20 is released from the flange 18, in which it is engaged, after which the frame 7 may be rotated upon its supporting-rollers 13 to the position desired. The plates 16 are slidably mounted each between radially-disposed guides 22. Each plate 16 has secured to it a downwardly-extending projection 23, longitudinally movable in a radial slot 24, provided in the plate 14. For releasably locking the plate 16 in the inner position four flat springs 25 are secured each at one end to the under side of the plate 14. The free end of each spring 25 has secured to it the lower end of an upwardly-extending pin 26, which extends through a hole provided in the plate 14 outside of the adjacent plate 16 when the

said plate is in the inner position. By pulling downward the free ends of the springs 25 the pins 26 may be withdrawn downward to a position in which the plates 16 may be retracted, together with their flanges 17, to the position indicated in dotted lines in Fig. 7, in which position the rollers 13 will pass through the recesses normally closed by the plates 16, thus permitting the frame 7 to be inserted into or withdrawn from the casing 3.

27 denotes the cylindrical lamp-reservoir, mounted centrally in the casing within the frame 7 and in a position such that the burner 28 will be disposed between the openings 5 and 6.

29 denotes a flap comprising, preferably, a metal plate hinged at one edge by means of a plate 30 to the under side of the plate 14. The plate 29 is provided at its inner end with an upwardly-extending curved flange 31, partially encircling the lamp-reservoir 27 and having hinged to it at one end a curved plate 32, which encircles the opposite side of the reservoir 27. The free ends of the plate 32 and the flange 31 are releasably secured together by means of a bolt 33, extending through said flange and plate and having mounted thereon a securing-nut 34. The plate 29 is secured in the horizontal position by means of two turnbuckles 35, rotatively mounted on the under side of the plate 14 and adapted to be turned, as shown in Fig. 2, to a position in which they will engage and lock the plate 29 in the horizontal position. Diametrically opposite sides of the plate 32 are provided with vertical slots 36, extending upwardly from the lower edge of said plate and provided each with a horizontal recess 37. The reservoir 27 of the lamp is provided on diametrically opposite sides with pins 38, adapted to be slipped upwardly in the slots 36 and laterally into the recesses 37, so as to support the lamp.

The burner 28 is mounted in a horizontal barrel 39, having its two ends closed, respectively, by the two lenses 40, disposed, respectively, in axial alinement with the openings 5 and 6. The barrel 39 is provided in its upper end with a chimney 40', which chimney discharges the products of combustion through a vertical opening 41 in the top of the casing 3. Suitable housings 42 and 43 of any desired construction are employed to protect the inner and outer portions of the casing, respectively, from the products of combustion passing from the chimney 40'. The housing 42 is tubular in form and has its upper end secured to the under side of the top of the casing and encircling the chimney 40' and opening 41. The housing 43 is mounted upon the top of the casing encircling the opening 41 and is closed at its upper end, the lower end being open and registering with the opening 41. Peripheral holes 44 are provided in the housing 43 to permit the

escape of the products of combustion. The lower side of the barrel 39 is provided with a vertical tubular extension 46, adapted to be inserted between the plate 32 and the flange 31. The tubular extension 46 is provided with two diametrically opposite slots 47, extending upwardly from the lower edge of the extension and having each a lateral recess 48. When the parts are in the position shown in Fig. 1, the slots 36 and 47 and recesses 37 and 48 register with each other, so that the lamp-reservoir 27 may be slipped upwardly to the position shown in Fig. 1, in which position the pins 38 will be located in the recesses 37 and 48.

In operating my invention, the parts having been assembled as shown in Fig. 1, when it is desired to change the signals the vertical arm of the right-angled wire 20 is swung inwardly, together with the free end of the spring 19, after which the frame 7 may be swung to a position in which the proper colored glasses will be interposed between the openings 5 and 6. To remove the lamp for the purpose of filling the reservoir with oil, the reservoir is turned to the left until the pins 38 are in alinement with the slots 36 and 47, after which the reservoir may be withdrawn. If it is desired for any reason to remove the frame 7, the lamp is first removed, after which the nut 34 is removed from the bolt 33, the bolt 33 is withdrawn, and the plate 32 swung so as to clear the extension 46. The turnbuckles 35 are then turned, so as to permit the plate 29 to be swung to the position shown in Fig. 5. The barrel 39 may now be removed. The plates 16 are then withdrawn outwardly, the springs 25 being depressed for that purpose, and the frame 7 is then turned until the rollers 13 register with the recesses normally covered by the plate 16, in which position the frame 7 may be withdrawn.

Various modifications of my invention may be made without departing from its spirit.

Having thus described my invention, what I claim, and desire to secure by Letters Patent, is—

1. In a caboose signal-lamp, the combination with a lamp, of a rotary tubular frame encircling the lamp and having a plurality of peripheral light-transmitting devices of different colors and provided with a plurality of peripheral supporting devices, a support for the frame having an opening through which the frame is insertible and provided with a plurality of recesses for admitting therethrough said peripheral supporting devices, and means for closing said recesses so as to form with the support a continuous track upon which the supporting devices may travel in a circle.

2. In a caboose signal-lamp, the combination with a lamp, of a rotary tubular frame encircling the lamp and having a plurality of

peripheral light-transmitting devices of different colors and provided with a plurality of peripheral supporting devices, a support for the frame having an opening through which the frame is insertible and provided with a plurality of recesses for admitting therethrough said peripheral supporting devices, means for closing said recesses so as to form a continuous track upon which the supporting devices may travel when the frame is rotated, and releasable means for locking the frame in different positions upon the support.

3. In a caboose signal-lamp, the combination with a lamp, of a rotary tubular light-transmitting frame encircling the lamp and having a plurality of peripheral supporting devices, a support having an opening through which the frame is insertible and having a plurality of recesses for admitting therethrough said peripheral supporting devices, means for closing said recesses so as to form with the support a track upon which said devices may travel when the frame is rotated, a support for the lamp movable to and from a position partly bridging said opening, and releasable means for locking the lamp-support in a position supporting the lamp axially in said frame.

4. In a caboose signal-lamp, the combination with a rotary tubular light-transmitting frame having a plurality of peripheral supporting devices, of a support having an opening through which the frame is insertible and having a plurality of recesses disposed so as to admit therethrough respectively said peripheral supporting devices, means for closing said recesses so as to form a continuous track upon which said devices may travel, and releasable means for locking the frame in different positions upon said support.

5. In a caboose signal-lamp, the combination with a rotary tubular light-transmitting frame having a plurality of peripheral supporting-rollers, of a support having an opening through which the frame is insertible and having a plurality of recesses disposed so as to admit therethrough said rollers respectively, means for closing said recesses, and means for releasably locking the frame in different positions on said support.

6. In a caboose signal-lamp, the combination with a rotary tubular frame carrying a plurality of light-transmitting devices, and having a plurality of peripheral supporting devices, of a support having an opening through which the frame is insertible and having a plurality of recesses disposed so as to admit therethrough respectively said peripheral supporting devices, and a plurality of slidable closures for closing said recesses and forming with said support a track upon which the supporting devices may travel when the frame is rotated.

7. In a caboose signal-lamp, the combina-

tion with a rotary tubular frame having a plurality of peripheral light-transmitting devices and having a plurality of peripheral supporting devices, of a support having an opening through which the frame is insertible and having a plurality of recesses disposed so as to admit therethrough said peripheral supporting devices respectively, a plurality of slidable closures for covering said recesses so as to form with said support a track upon which said devices may travel when the frame is rotated, and releasable means for locking the frame in different positions upon said support.

8. In a caboose signal-lamp, the combination with a rotary tubular frame having a plurality of peripheral light-transmitting devices and having a plurality of peripheral supporting-rollers, of a support having an opening through which the frame is insertible and having a plurality of recesses disposed so as to admit therethrough said rollers respectively, slidable closures for covering said recesses so as to form with said support a track upon which the rollers may travel, and releasable means for locking the frame in different positions upon the support.

9. In a caboose signal-lamp, the combination with a rotary tubular frame carrying a plurality of light-transmitting devices and having a plurality of peripheral supporting-rollers, of a support having an opening through which the frame is insertible and provided with an upwardly-extending annular track encircling said opening, said track having a plurality of inwardly and outwardly movable segments which, when moved to the outer position, form recesses for admitting therethrough the said rollers respectively, and when moved to the inner position, complete the track upon which the rollers may travel in a circle, releasable means for locking the frame in different positions upon said support, and releasable means for locking the track-segments in the inner positions.

10. In a caboose signal-lamp, the combination with a support having a vertical opening, of a lamp-support hinged to said support and movable to and from a horizontal position, said lamp-support being provided with means for retaining said lamp in the center of said opening when the lamp-support is horizontally disposed, releasable means for locking the lamp-support in the horizontal position, a rotary tubular frame adapted to encircle the lamp when the lamp-support is in the horizontal position, said frame having a plurality of peripheral light-transmitting devices and provided with peripheral supports adapted to rest upon the first-named support, said first-named support being provided with a plurality of recesses communicating with said opening for admitting therethrough said peripheral supports, and means for closing

said recesses so as to form with said supports a track upon which said supporting devices may travel when the frame is rotated.

11. In a caboose signal-lamp, the combination with a support having an opening, of a flap hinged to said support so as to swing to and from a horizontal position and provided with means for supporting, when in the horizontal position, a lamp centrally in said opening, releasable means for locking the flap in the horizontal position, a frame encircling the lamp and rotatively mounted on said support and provided with a plurality of peripheral light-transmitting devices, and a lamp carried by said flap and disposed so as to have its light shine through said transmitting devices.

12. In a caboose signal-lamp, the combination with a support having an annular track and an opening encircled by said track, of a lamp disposed centrally in said opening, a rotary frame encircling said lamp and provided with a plurality of peripheral light-transmitting devices, a plurality of rollers mounted on said track and supporting said frame, and releasable means for locking the frame in different positions relative to said support.

13. In a caboose signal-lamp, the combination with a casing having an open lower end and front and rear openings, of a lamp disposed in said casing so as to have its light shine through said front and rear openings, a rotary tubular frame encircling said lamp and rotatable around said lamp in said casing and provided with a plurality of peripheral light-transmitting devices disposed, so that when the frame is rotated, the light-transmitting devices may be interposed between the lamp and the front and rear openings, and releasable means for locking the frame in different positions.

14. In a caboose signal-lamp, the combination with a casing having front and rear openings and an open lower end, of a rotary tubular frame having a plurality of light-transmitting devices so disposed that the said devices may be registered consecutively with the front and rear openings when the frame is rotated to different positions in the casing, releasable means for locking the frame in said different positions, a lamp adapted to be disposed centrally in said frame between said front and rear openings, a swinging support for said lamp and upon which said lamp may be swung out of said frame through the open end of the casing, and releasable means for locking the support in a position in which the lamp is disposed between the front and rear openings of the casing.

15. In a caboose signal-lamp, the combina-

tion with the caboose-roof having a vertical opening, of a casing mounted on said roof and having an open end registering with the opening in the roof and provided with front and rear openings, a lamp located in said casing between the front and rear openings thereof, a rotary tubular frame in said casing and encircling said lamp and provided with a plurality of light-transmitting devices so disposed that when the frame is rotated each of said devices may be made to register consecutively with said front or rear openings, and releasable means for locking the frame in different positions in said casing.

16. In a caboose signal-lamp, the combination with the caboose-roof having a vertical opening, of a casing having an open lower end registering with said opening and provided with front and rear openings, a lamp located in the casing between the front and rear openings and insertible in the casing through the opening in the roof, a rotary tubular frame encircling said lamp and rotatable in said casing to three different positions and carrying three green and one red glasses disposed so that each may be interposed between the lamp and the front or rear openings, and releasable means for locking said frame in either of said three positions.

17. In a caboose signal-lamp, the combination with the caboose-roof having a vertical opening, of a casing having front and rear openings and mounted on said roof and provided with an open lower end registering with the opening in the roof, a tubular frame rotative in the casing to three different positions and provided with three green and one red glasses disposed so as to register each with either said front or rear opening when the frame is rotated to the proper position, said frame being provided with a plurality of peripheral rollers, a support secured to the under side of said roof and provided with an opening through which the frame is insertible and having a plurality of recesses communicating with said opening for admitting therethrough the peripheral rollers, means for closing said recesses, releasable means for locking said frame in said three positions, a lamp adapted to be disposed between said front and rear openings of the casing and located centrally in the frame, and a support for said lamp.

In testimony whereof I affix my signature in presence of two subscribing witnesses,

DUDLEY H. FLYNT.
